ROOF VENTILATOR

Elmer W. Petersen and Raymond F. Sansonetti,
Chicago, Ill.

Application January 5, 1946, Serial No. 639,316

7 Claims. (Cl. 98—42)

1

Our invention relates to ventilators for attic and other compartments in buildings having pitched roofs, it being the custom to make an opening in the roof and apply means thereover to permit ventilation while keeping out rain and wind.

The invention consists in a chamber applicable as stated and having for its object to serve the purpose efficiently.

A further object of the invention is to provide means in the chamber automatically responsive to changes in climatic temperature, in order that the roof may be protected against cold weather without the necessity of manual attention or adjustment.

A further object of the invention is to so design the novel chamber that its temperature control also operates in conjunction with the chamber to close the ventilator during a storm or blizzard.

An important object of the invention is to construct the same along lines of simplicity and of few parts, in order that the ventilator may be economically produced and sold at a reasonable figure.

With the above objects in view and any others which may suggest themselves from the description to follow, a better understanding of the invention may be had by reference to the accompanying drawings, in which—

Fig. 1 is a perspective view, showing the ventilator on a reduced scale mounted on a pitched roof, the tar paper or other covering thereof not being shown;

Fig. 2 is a side elevation of the ventilator;

Fig. 3 is a front end view;

Fig. 4 is a top plan view;

Fig. 5 is an enlargement of the frontal portion of the ventilator, showing a section of its chamber and interior as taken on the line 5—5 of Fig. 6;

Fig. 6 is a partial section of the ventilator taken on the line 6—6 of Fig. 4, and drawn on an enlarged scale showing the ventilator fully open;

Fig. 7 is a view similar to Fig. 6, showing the ventilator closed; and

Fig. 8 is a section taken on the line 8—8 of Fig. 6, the medial portion of the showing being broken away and the side portions gathered.

Referring specifically to the drawings, 10 denotes a sheet metal front base frame forming the front bottom portion of the ventilator and adapted to be laid on a roof 11 as indicated in Fig. 1, while 12 is a sheet metal rear base frame

2

portion of the ventilator and having its forward portion lying in overlapping engagement with the rear portion of the front base frame 10 secured thereto by welding or the like. It is understood that the base frames 10 and 12 will be overlaid with the tar paper or other roof covering on all sides.

Upon the rear portion of the frame 10 are soldered the frontal portions of the outward base flanges 12 of the ventilator side walls 13, these being high in the frontal region and tapering to points at the rear. The top 14 of the ventilator is trained to follow the upper edges of the side walls 13, and these walls 13 have top marginal flanges 15 overlapping and soldered to the top 14. A chamber 16 is thus formed which is closed at the sides and rear and open in front.

Figs. 3 and 6 show that the frontal opening of the ventilator is occupied by a fly screen 17, the same being carried by a sheet metal frame 18. A retainer for the upper end of this frame is formed by bending the top 14 out with a deflected flange 19 having a return bend 20 as a reinforcement and stop for the frame 18; and Figs. 6 and 8 show that the portion 21 of the base frame 10 which is inside the ventilator is formed with a return fold 22. Beyond the latter the base portion 21 carries forwardly extending individual side strips 23 having external upward flanges 24 immediately in front of the lower portion of the screen frame 18, such flanges forming retainers for the lower portion thereof. The side strips 23 are secured to the base 10 by welding or the like. It may also be pointed out at this time that the base frame 10 and the side flanges 12 are formed with inclined upward side folds 25 and 25a, respectively, as more clearly shown in Fig. 3, these forming gutters to check the seepage of rain water under the tar paper covering 26. This eliminates the sealing of the base frame with a roofing cement.

While the ventilator, considered as an enclosure, may be suitable to a large extent toward shielding the roof opening from the entrance of rain or wind, it is still possible that such elements may enter by way of the screen 17. We have therefore provided a control in the side of the frontal portion of the ventilator designed to close the ventilator when the weather becomes cold and at the same time check the entrance of rain, snow or wind by way of its frontal opening. Accordingly, Figs. 5 and 6 show that the control is generally in the form of a horizontally positioned cylinder 30, the same having ends 31. The latter have cut out portions 32 and 33 on oppo-

site sides, the portion 33 facing the frontal opening of the ventilator. The cylinder 30 is designed for partial rotation in the chamber 16, and is therefore mounted on an axial rod 34 which is journaled in the side walls 13 of the chamber 16, these being preferably bulged as indicated at 25 to form journals. Thus, the cylinder 30 is shown in the open position in Fig. 6 and rotated to the closed position in Fig. 7.

The cylinder 30 is made of sheet metal, and most of the material in the top of the opening 33 is bent forward with a double flange 36. Thus, when the cylinder rotates from the open position of Fig. 6 to the closed one of Fig. 7, the flange 36 meets at inclined return flange 37 made from the section 22 of the base frame 10, as shown in Fig. 7, so that the rotation of the cylinder is stopped. On the return travel, the left-hand wall of the cylinder—as seen in Fig. 7—meets the same inclined flange 37, as indicated in Fig. 6, to stop the rotation of the cylinder.

The ends 31 of the cylinder 30 are spaced from the side walls 13 of the chamber 16, as clearly indicated in Fig. 5, and frontal shields are provided for the spaces to check the passage of rain or wind through the same. Thus, the cylinder flange 36 is cut short of the cylinder ends, and the end portions 36a of the flanges are bent back into the cylinder, leaving the adjacent peripheral portions thereof clear. The shields referred to are arcuate strips 38 soldered with their outer edges to the side walls 13 of the housing, the strips following the curvature of the cylinder freely and overlapping the said peripheral portions as shown in Fig. 5.

The rotation of the cylinder 30 may only be partial most of the time, and in such event a passage may exist through the same for rain or wind. To counteract this tendency, the cylinder wall 30 is made fiat adjacent to the lower end of the opening 33, as indicated at 39, so that when the cylinder rotates in the clockwise direction—as seen in Fig. 6—the front edge of the portion 39 will slope to form a baffle against the entrance of rain or wind into the rear portion of the ventilator. Also, the portion 39 forms a drain for the rain striking the same to fall into the gutter formed by the base frame portion 22 and the flange 37. The ends of this gutter are formed by the side walls 13 of the chamber 16, and such ends are made with perforations 40 for the discharge of water accumulated in the gutter.

Since storms or blizzards are generally attended by a fall of temperature, this factor is employed to constitute the cylinder 30 and automatic control for regulating the ventilator. Thus, a bi-metal coil 41 is disposed between one of the cylinder ends 32 and adjacent wall 13, the inner end of the coil being driven through the shaft 34, and its outer end being carried by a hook 42. This hook is formed with a screw shank 43 which passes freely through a bearing 44 carried by the wall 13; and nuts 45 are mounted on the screw on both sides of the bearing. With the coil 41 mounted as just described, its thermostatic property may be such as to rotate the cylinder 30 toward its baffling position during a predetermined fall of temperature. Further, if the timing or latitude of the control requires changing to suit a different climate, it is an easy matter to loosen the nuts 45 and adjust the shank 43 of the hook 42 to tension or relax the coil 41.

It will be evident from the above description that we have provided a ventilator which auto-

matically controls its inlet against the entrance of rain, snow or wind when these weather characteristics are accompanied by a fall of temperature. In such event, the cylinder 30 automatically turns to reduce the amount of cold air entering the building by way of the ventilator and also form a baffle against the entrance of wind. Further, the ventilator is constituted to check the entrance of rain or excessive wind where the cylinder is partially open or closed. Further, the control has its own rain deflector and gutter to clear the ventilator of water accumulated during a rain storm. Further, the thermostatic control is concealed in the housing and protected from rain and dust. Further, the ventilator housing has simple retaining means for its screen frame, so as to eliminate the need of solder to secure the same. Further, the base frame of the ventilator is flanged at the sides to check the seepage of rain water under the roofing material of the building. Finally, the ventilator is made up of few parts and is adjustable to suit different climatic conditions.

While we have described the invention along specific lines, various minor changes or refinements may be made therein without departing from its principle, and we desire to consider such changes and refinements as coming within the scope and spirit of the appended claims.

We claim:

1. A ventilator for an opening in a pitched roof comprising front and rear base frames, the rear frame being perforated to clear the opening, a housing rising inclinedly over the latter from the rear base frame and having an entrance opening in its lower end, a hollow cylinder journaled endwise between the side walls of the housing, said cylinder having oppositely disposed cutout portions along its wall and defining front and rear wall sections, one edge of each of the wall sections bent outwardly to form a flange, and a projection between the vertical plane of the axis of the cylinder and the plane of the entrance opening and extending from said base frame and cooperating with either one of the wall section flanges to permit only the partial rotation of the cylinder in either direction.

2. The structure of claim 1, said projection being a back bend of the front base frame and forming a channel between said side walls.

3. The structure of claim 1, said projection being a back bend of the front base frame and forming a channel between said side walls, and the latter being perforated opposite the ends of the channel.

4. The structure of claim 1, said projection being a back bend of the front base frame and forming a channel between said side walls, the rear cylinder wall section having a flattened portion lengthwise of one of its edges to discharge into said channel rain water entering the cylinder from said entrance opening.

5. The structure of claim 1, the ends of the cylinder being spaced from the side walls of the housing, and shields between the cylinder and said side walls at each end of said entrance opening.

6. The structure of claim 1, the ends of the cylinder being spaced from the side walls of the housing, and shields between the cylinder and said side walls at each end of said entrance opening, such shields being arcuate strips secured with their outer edges to said side walls and curved to follow the curvature of the cylinder.

periphery and freely overlap the end portions thereof.

7. A ventilator for an opening in a pitched roof including front and rear base frames, the rear frame being perforated to clear the opening, a housing rising inclinedly over the latter from the rear base frame and having an entrance opening in its lower end, and a cylinder mounted in the housing and having oppositely disposed cut-out portions and front and rear wall sections, said cylinder controlling the amount of atmospheric communication between said openings, a framed screen filling said entrance opening, and means extended from the housing and front base frame to retain the framed screen, such means comprising a deflected flange projecting outwardly from the housing material over the entrance opening, strips extending forwardly from the inner portion of the front base frame and extending beyond the side portions of the entrance

opening, and upward external flanges extending from the strips and overlying the side portions of the framed screen.
